UNITED STATES PATENT OFFICE

RALPH R. SMITH, OF JACKSON HEIGHTS, NEW YORK, ASSIGNOR TO NATIONAL CARBON COMPANY, INC., A CORPORATION OF NEW YORK

BATTERY HAND LAMP

Application filed March 22, 1926. Serial No. 96,598.

This invention relates to improvements in electric lighting devices such as battery hand lamps or flashlights, and more particularly to improvements in mechanism for focusing the incandescent lamps thereof.

In focusing flashlights similar to the one disclosed in U. S. Patent No. 1,668,881 granted May 8, 1928, upon an application Serial No. 466,639, filed May 4, 1921, in the name of

10 Lee J. Voorhees, the reflector and adjustable lamp holder are combined as a unit, which unit is secured in the battery case by a lens ring that clamps the reflector. In some flashlights it is desirable to mount the lamp holder 15 independently of the reflector, so that the latter shall be easier to manufacture, assemble and keep clean. It is also important that the lamp and the holder carrying it shall be guided accurately along the focal axis of the 20 reflector during the focusing movement. A further object is to provide an improved lens and reflector assembly in which the parts may be separated at will but shall be prevented from accidental separation when the assembly 25 is removed from the casing.

According to the present invention, the lamp holder is slideable in a guide that is coaxially mounted in and insulated from the head end of the lamp casing, the lamp holder 30 being provided with flanges at its ends to guide it accurately along the axis of the casing. A centrally apertured reflector is so secured to the head end of the casing that it may be removed for cleaning, when desired, without disturbing the lamp and lamp holder assembly, and may be accurately replaced with its aperture so positioned that the lamp bulb may properly project therethrough.

40 The objects and novel features of this invention will be apparent from the following description, taken with the accompanying drawing which is a central longitudinal sectional view of a focusing flashlight embodying this invention.

In the drawing, 10 designates a tubular casing of metal or other suitable material that is adapted to contain the usual battery of dry cells B, which furnish current to light the lamp filament. These cells may be in-

serted and removed through the bottom end of the casing, which has a closure cap 11 carrying therein a conductive shell 12 forming a compartment to hold spare bulbs and engaging the bottom of the battery to hold the latter in place. The closure cap 11 is threaded onto the threaded lower end of the casing, as at 13, whereby the cap is adjustable axially of the casing to move the battery and focus the lamp, as will be explained.

The head end of the casing is enlarged slightly and threaded, as at 15, to receive a similarly threaded head fitting 16 which encloses the reflector R and supports the lens ring 17 carrying the reflector and the lens or cover glass E in front of the reflector. An inturned flange 18 is provided on the fitting to form a supporting surface for an annular insulating washer 19. An outturned flange 20 on the reflector seats on the washer 19 and the lens E rests on the flange 20. The lens, reflector and washer are clamped against the flange 18 by the lens ring 17 which has an inwardly beveled part to engage the beveled part of the lens and a threaded skirt 21 coupled to a similarly threaded part 22 of the fitting 16. The periphery of the insulating washer 19 projects into a groove 23 in the lens ring, and supports the reflector and lens and prevents them from falling out of the ring 17 when the lens ring assembly is removed from the fitting 16. However, the washer 19 is sufficiently yieldable to permit it to be forced past the shoulder 24 on the lens ring to separate the lens and reflector from the lens ring when it is desired to clean the parts.

The reflector has a central aperture 25 through which the incandescent lamp L projects. The lamp is mounted in a holder H that is slideable in a guide G axially of the aperture 25 and casing 10. The guide G is disposed within and secured to an insulating tube or sleeve D tightly and frictionally fitting inside the enlargement 15 and abutting at one end against the interior shoulder 26, while the other end projects beyond the end of the casing body.

The reflector and lamp holder are thus supported independently of one another, whereby the reflector assembly may be re-

5 moved and replaced without disturbing the lamp, lamp holder and focusing assembly. Moreover, the lamp holder focusing assembly may be inserted and withdrawn as a separate unit. The guide G may be a metal shell that has a flaring upper end or flange 28 provided with an outturned flange 29 at its upper end resting upon the upper end of the insulating tube D. The flange 28 closes 10 the end of the tube D and case 10, and a number of outward punches 30 therein extend into the insulation D to hold the guide in place and against rotation.

15 The improved lamp holder H is slidable axially within the guide G, and is desirably a machined metal piece internally threaded to receive the usual threaded base of the incandescent lamp L. At its upper end the lamp holder has an integral collar 32 having a sliding fit in the guide G and is recessed at 32' to receive a longitudinal rib 33 within the wall of the guide to prevent rotation of the holder as it moves lengthwise of the guide. The guide is also provided 20 with a circumferential interior bead 34 that provides a shoulder to engage the collar 32 and limit the movement of the holder in one direction. The other end of the holder H is formed with a reduced section 35 providing narrow inner and outer shoulders, respectively receiving the insulating discs 36, 37 and a metal collar 38, which are firmly secured to the holder by riveting or spinning over the end of the part 35, as shown. 25

30 The insulating discs 36 and 37 clamp between them the conductive means whereby current is carried from the center battery contact B' to the center lamp contact. Such means may consist of an inverted cup-shaped contact 39 that is engageable by the center battery contact, and a metal plate 40 carrying a spring contact 41 projecting through a hole in the disc 36 and adapted to engage the center lamp contact. The disc 37 35 is annular and the disc 36 is cup-shaped, the two discs tightly clamping together a flange on the contact 39 and the plate 40 of the contact 41.

30 The collar 38 also has a sliding fit in the guide G and, with the collar 32, provides a long bearing for the holder and accurately guides the lamp holder axially of the guide and casing. In addition, the collar 38 serves as a bearing for one end of the helical spring S that is confined in the space between the holder and guide and has its other end bearing against an annular spring seat 43 which freely fits around the holder and engages against the under side of the internal bead 45 or shoulder 34.

65 The spring S is thus compressible during the movement of the holder in one direction,—that is, toward the front end of the lamp, and its limit of compression serves to limit the movement of the lamp in that di-

rection. When the compressing force is released, the spring S operates to positively move the lamp holder and lamp in the opposite direction until such movement is limited by the collar 32 engaging the bead 34. 70 Between these limits of focusing movement, the lamp filament may be positioned in the focus desired with relation to the reflector R.

The focusing movement is effected by rotating the bottom cap 11 in the proper direction. 75 By screwing the cap onto the casing, the battery is pressed forward by the shell 12, and, the pressure of the battery against the lamp holder slides the latter to move the lamp and its filament outwardly along the reflector axis. 80 This movement also compresses the spring S but the parts are held in any adjusted position by the friction of the interfitting threads at 13. Reverse rotation of the cap 11 allows the spring S to expand to move the holder H and lamp L inwardly to change the position of the filament relatively to the focus of the reflector. In both directions of movement, the battery is moved and guided along with the holder, and its electrodes are maintained in contact with the conductive contacts 12 and 39. The current supply to the lamp may be controlled by a suitable switch W which has one contact in circuit with the casing and its other contact connected to a conductor 44 which engages the flange 28 of the guide G. When the switch is closed and the lamp is lighted, the path of the current is from the center battery electrode B', through the contact 39, plate 40, spring contact 41 to the center lamp contact; through the lamp filament and threaded outer lamp contact to the holder H and guide G; thence from the flange 28 through the conductor 44, switch W, casing 10, cap 11 and shell 12 to the other electrode of the battery. 95

100 While the improved construction is shown in detail it will be understood that minor changes may be made in various features without departing from the principles of the invention. 110

I claim:

1. A battery hand lamp comprising the combination of a casing; a reflector carried thereby and having an aperture; a guide mounted within said casing independently of said reflector; an incandescent lamp projecting through said aperture; a lamp holder slideable along said guide; and means whereby said lamp holder is adjustable in opposite directions axially along said guide; said holder having spaced collars cooperating with an intermediate part of said guide to limit the movement of said holder. 115 120

2. A battery hand lamp comprising the combination of a casing having an inturned flange and a threaded portion adjacent said flange; a washer on said flange having a peripheral edge projecting outside the outline of said threaded portion; a reflector hav- 125 130

ing a marginal flange seated on said washer but narrower than the latter; a lens seated on said reflector flange; and a lens ring engaging said lens and having a threaded skirt interfitting with said threaded portion of the casing to clamp said lens, reflector, and washer against said flange, said lens ring having an interior groove to receive and retain the peripheral edge of said washer, said washer being yieldable at will to release said reflector and said lens from said ring.

3. In a focusing battery hand lamp, a casing; a reflector, a lens and a lens ring thereon removable and replaceable as a unit; in combination with a slidable non-rotatable lamp holder, a guide therefor and a support for said guide removable and replaceable as a unit independently of the first mentioned unit.

20 4. A battery hand lamp comprising the combination of a casing; a reflector; a lens; a rotatable lens ring for clamping said reflector and lens to said casing; and means carried by said lens ring to prevent accidental separation of said reflector and lens therefrom but permitting their removal at will; said means comprising an insulating washer having its peripheral edge received and retained in a groove in said ring.

25 5. A focusing battery hand lamp comprising the combination of a casing; a reflector insulated from and carried by said casing; an insulating tube within and carried by said casing; a guide having a flange supported by said insulating tube and a reduced portion spaced from said tube; a lamp holder slidably axially in said reduced portion of said guide and a spring cooperating with said holder and guide.

In testimony whereof, I affix my signature.
RALPH R. SMITH.
